US0D1097438S

(12) **United States Design Patent** (10) **Patent No.:** **US D1,097,438 S**
(45) **Date of Patent:** **** Oct. 7, 2025**

(54) **PALLET WITH ANTI-SLIP FEATURE**

(71) Applicant: **Polymer Solutions International Inc.**,
Medford, NJ (US)

(72) Inventors: **John Spadavecchia**, Atlantic Beach,
NC (US); **Jerry Koefeld**, Lake Bluff,
IL (US); **Jeffrey Jacobs**, Lexington, SC
(US); **Walter T. Blanchard**, Alamo
Heights, TX (US)

(73) Assignee: **Polymer Solutions International Inc.**,
Medford, NJ (US)

(**) Term: **15 Years**

(21) Appl. No.: **29/884,809**

(22) Filed: **Feb. 16, 2023**

(51) **LOC (15) Cl.** **09-08**

(52) **U.S. Cl.**

USPC **D34/38**

(57) **CLAIM**

The ornamental design for a pallet with anti-slip feature as shown and described.

DESCRIPTION

FIG. 1 is a top side perspective view of a rib-top pallet with anti-slip feature showing our new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The portions of the pallet with anti-slip feature shown in dash-dot broken lines are for illustrative and environmental purposes and form no part of the claimed design.

1 Claim, 4 Drawing Sheets
